UNITED STATES PATENT OFFICE.

JOHN P. WIENS, OF MILWAUKEE, WISCONSIN.

DESIGN FOR A HANDLE-BRACE.

SPECIFICATION forming part of Design No. 32,812, dated June 12, 1900.

Application filed May 5, 1900. Serial No. 15,651. Term of patent 7 years.

To all whom it may concern:

Be it known that I, JOHN P. WIENS, a citizen of the United States, residing at Milwaukee, in the county of Milwaukee and State of Wisconsin, have invented and produced a new and original Design for a Handle-Brace; and I do hereby declare the following to be a full, clear, and exact description of the same, reference being had to the accompanying drawings, forming a part thereof.

In the said drawings, Figure 1 is a plan view; Fig 2, a side elevation; Fig. 3, a longitudinal sectional view taken on the line 3 3 of Fig. 1; Fig. 4, a transverse sectional view taken on the line 4 4 of Fig. 1; Fig. 5, an end elevation, and Fig. 6 a bottom plan view of a handle-brace embodying my new design.

My design relates to the new and original shape or configuration of the article.

The leading or essential feature consists in the unitary design for a handle-brace, made the subject of illustration, comprising the shape of the flat horizontal base A, having straight sides *a a* and convexly-rounded ends *b b*, the shape of the end portions B B having obliquely-disposed circular flat upper surfaces extending downwardly and outwardly from the highest plane of the transversely-rounded convex upper portions *c c* toward the

two ends, with inclined spirally-corrugated 30 bores C C extending entirely therethrough, the angle of inclination of each bore C being exactly opposite the angle of inclination of the upper flat surface of the end through which it extends, the transverse central de- 35 pressed part D being between transverse vertical walls *d d*, and said part D having a flat upper surface with a central vertical smooth-walled bore E, extending down entirely through the base, and elliptical obliquely- 40 disposed depressions F F at each side thereof, and the shape of the transverse semicircular bands G G inclining inwardly toward the center between the said transversely rounded convex upper portions *c c* and the transverse 45 vertical walls *d d* at each end of the central depressed portion D.

Having thus described my invention, what I claim as new, and desire to secure by Letters Patent, is—

The design for a handle-brace, substantially as herein shown and described.

In testimony whereof I affix my signature in presence of two witnesses.

JOHN P. WIENS.
